Primary Examiner — Daniel J Domino

Assistant Examiner — Ana M. Vine

CLAIM

The ornamental design for a display screen or portion thereof with print icon, as shown and described.

DESCRIPTION

FIG. 1 is a front view of an enlarged portion of a display screen or portion thereof with print icon showing the new design; and,

FIG. 2 is a front view of the display screen or portion thereof with print icon of FIG. 1 shown with additional broken line subject matter.

The outermost dashed broken lines in FIG. 2 depict a display screen or portion thereof that form no part of the claimed design. The remaining broken lines illustrate portions of a graphical user interface and the icon that form no part of the claimed design.

1 Claim, 2 Drawing Sheets
